CASING FOR A FAN OR THE LIKE

Wilfred O. Langille, Chester, and Charles F. Bruder, Ridgewood, N. J., assignors to The Singer Manufacturing Company, Elizabeth, N. J., a corporation of New Jersey

Application June 2, 1950, Serial No. 10,304

Term of patent 14 years

(CL. D26—7)

To all whom it may concern:

Be it known that we, Wilfred O. Langille and Charles F. Bruder, citizens of the United States, residing respectively at Chester, in the county of Morris; and at Ridgewood, in the county of Bergen and State of New Jersey, have invented a new, original, and ornamental Design for a Casing for a Fan or the like, of which the following is a specification, reference being had to the accompanying drawing, forming a part thereof.

Fig. 1 represents a perspective view of a casing for a fan, showing our new design.

Fig. 2 represents a rear elevation view of the unit shown in Fig. 1, it being understood that the left, right and rear side faces of the unit are all similar in appearance.

We claim:

The ornamental design for a casing for a fan or the like, substantially as shown and described.

WILFRED O. LANGILLE.
CHARLES F. BRUDER.
